(57) **CLAIM**

The ornamental design of a drip tray, as shown and described.

DESCRIPTION

FIG. 1 is a top, left, rear perspective view of a drip tray, according to my new design;

FIG. 2 is a top view of the design of FIG. 1;

FIG. 3 is a bottom view of the design on FIG. 1;

FIG. 4 is a right side view of the design of FIG. 1;

FIG. 5 is a left side view of the design of FIG. 1;

FIG. 6 is a front view of the design of FIG. 1;

FIG. 7 is a rear view of the design of FIG. 1; and,

FIG. 8 is a sectional view taken along line 8-8 of FIG. 3. The broken lines in FIGS. 1-3 depict portions of the drip tray that form no part of the claimed design.
